UNITED STATES PATENT OFFICE

172,866

CHEST

Peter Cuccio, Los Angeles, Calif.

Application March 22, 1954, Serial No. 29,647

Term of patent 3½ years

(Cl. D58—12)

To all whom it may concern:

Be it known that I, Peter Cuccio, a citizen of the United States and resident of Los Angeles, in the county of Los Angeles and State of California, have invented a new, original, and ornamental Design for a Chest, of which the following is a specification, reference being had to the accompanying drawing, forming a part thereof.

The bottom of the chest is plain.

I claim:

The ornamental design for a chest, substantially as shown and described.
